UNITED STATES PATENT OFFICE.

JESSE J. BROWN, OF HAYWARD, CALIFORNIA.

ROCK AND SAND HEATER AND GRADER.

Application filed October 8, 1921. Serial No. 506,393.

To all whom it may concern:

Be it known that I, JESSE J. BROWN, a citizen of the United States, residing in Hayward, Alameda County, and State of California, have invented a new and useful Improvement in a Rock and Sand Heater and Grader, of which the following is a specification.

My invention relates to improvements in rock and sand graders and heaters wherein a revolving grading screen operates in conjunction with grading chutes arranged to form a tortuous passage through a heating chamber, within which the screen is mounted, to grade and heat sand and rock for asphalt road building purposes.

The primary object of the present invention is to provide a new and improved rock and sand heater and grader. Another object of the present invention is to provide a new and improved rock and sand heater of simple construction and having few parts of simple and cheap manufacture, to reduce the cost of producing and maintaining the device.

A further object of the invention is to provide an improved rock and sand heater and grader arranged to expose the rock and sand to the action of heat through a period of time substantially proportionate to the mass of the separate particles whereby the entire mass may be uniformly heated.

A still further object of the invention is to provide a revolving screen mounted directly within a heating chamber and arranged to heat and grade a mixture of rock and sand into separate grades, and to separately deliver said grades.

I accomplish these several features by means of the improved device disclosed in the drawings forming a part of the present specification wherein like characters of reference are used to designate similar parts throughout the said specification and drawings, and in which:

Fig. 1 is a vertical longitudinal sectional view of my improved rock and sand heater and grader, disclosing the manner in which the tortuous heat passages are formed by the grading chutes;

Fig. 2 is a transverse sectional view fur-

ther disclosing the arrangement of the tortuous heat passages; and

Fig. 3 is an end elevation of the device.

Referring to the drawings the numeral 1 is used to designate in general a suitable housing whose interior constitutes a heating chamber 2, the lower portion of said chamber 2 being provided with fire-brick or lining 3 to provide a fire-box heated by a suitable burner 4.

Above the fire-box are arranged a series of inclined converging delivery chutes 6 and still higher two series of oppositely inclined baffle plates 7 and between said chutes 6 and 7 are provided partitions 8 extending, at a point immediately above the chutes, only part way across the heating chamber 2, the said chutes, plates and partitions being arranged to form tortuous heat passages upward from the fire-box to the top of the heating chamber 2 and to a suitable stack 11 at the top of the housing 1.

A revolving screen 12 is rotatably mounted at a slight angle within the upper portion 75 of the heating chamber 2 and is provided with screen sections of successively enlarged mesh, the smaller mesh being at the upper end of the inclined screen 12, the purpose of which will hereinafter be more fully set forth.

A suitable filling or supply chute 14 is arranged to feed material into the upper end of the screen 12 and a suitable pulley 15 is provided at the lower end of the shaft 85 16 which supports the screen 12 so that said screen may be rotated from any suitable source of power, not shown.

In practice a mixture of sand and rock of different sizes is introduced into the upper end of the screen 12 through the feeding chute 14. As the screen 12 is revolved the material therein is agitated to facilitate exposure of the particle of the material therein to the action of heat passing from the fire-box through the tortuous passages around the chutes 6 and partitions 8. As the particles of sand contain less mass than the particles of rock, said sand particles will be heated much more quickly than the particles of rock.

As the sand is heated and the dampness

removed therefrom by the action of said heat, said heated particles of sand will be precipitated through the finer meshes at the upper end of the screen 12 and onto the oppositely inclined baffle plates 7 which plates are also heated by the action of heat passing through the heating chamber 2 and screen 12 thereby further heating the sand.

The coarser material held within the screen 12 by the finer meshes at the upper end thereof will be held within the screen and agitated for a longer period of time than the sand and, therefore, subjected to the action of the heat passing through said screen for a longer period, until said coarser particles reach a portion of the successively larger meshes which will permit their passage.

This retention of the coarser material within the revolving screen is a novel feature of the present invention as it produces a uniformly heated material when the various grades are again assembled within the asphaltic mixture and further effects a saving of heat and fuel for the reason that no portion is held long enough to be overheated while waiting for sufficient heat to be imparted to the other particles of the mixture.

The still coarser particles are further retarded by the grading facilities of the revolving screen until they are carried to the proper meshes which will permit their passage. Briefly, the particles are held within the screen and agitated by the rotation thereof and exposed to the action of heat passing through the said screen through a period proportionate to the mass of the separate particles, thereby securing a uniformly heated mass when the separated and graded particles are again assembled in an asphaltic mixture.

These particles are further heated in their passage over the heated and oppositely inclined baffle plates 7 as well as by passing through the heat of the tortuous passages which passages extend between said baffle plates 7 as well as between and around the delivery chutes 6.

It is thus obvious that the period of time consumed by the passage of any particle through the screen and heating chamber is proportionate with its mass. Or in other words, the particle is retarded in its passage through the heating chamber so that the period of time during which said particles are exposed to the action of heat within the heating chamber is proportionate to its mass, thereby effecting a uniform heat to all particles of all sizes.

Having thus described my invention what I claim as new and desire to secure by Letters Patent is:

1. A rock and sand heater and drier comprising a heating chamber; grading chutes mounted within said chamber and arranged

to form tortuous heat passages upwardly through said chamber; a revolving screen mounted within the chamber and above the grading chutes therein, said screen having sections of successively enlarged meshes whereby material introduced thereinto may be retained and exposed to the action of heat within the chamber during a period of time substantially proportionate to the mass of particles of said material; and means for revolving the screen to facilitate exposure of the material therein to the action of heat within said chamber.

2. A rock and sand heater and grader comprising a heating chamber; a series of inclined grading chutes mounted within the chamber and arranged to form tortuous heat passages through said chamber; a revolving screen mounted within said chamber and above the chutes therein and arranged to grade and separate rock and sand delivered therein and to deliver separate grades to separate chutes; and inclined baffle plates arranged below the screen and above the chutes and arranged to receive the graded material from said screen and to deliver the same to said chutes through the tortuous heat passages.

3. A rock and sand heater and drier comprising a heating chamber; grading chutes mounted within said chamber and arranged to form tortuous heat passages upwardly through said chamber; a revolving screen mounted within the chamber and above the grading chutes therein, said screen having sections of successively enlarged meshes whereby material introduced thereinto may be retained and exposed to the action of heat within the chamber during a period of time substantially proportionate to the mass of the particles of said material; means for revolving the screen to facilitate exposure of the material therein to the action of heat within said chamber; and means for delivering material to the screen at the end thereof containing the smallest mesh.

4. A rock and sand heater and grader comprising a heating chamber; a series of inclined grading chutes mounted within the chamber and arranged to form tortuous heat passages through said chamber; a revolving screen mounted within said chamber and above the chutes therein and arranged to grade and separate rock and sand delivered therein and to deliver separate grades to separate chutes; and inclined baffle plates arranged below the screen and above the chutes and arranged to receive the graded material from said screen and to deliver the same to said chutes through the tortuous heat passages; and means for delivering material to the screen at the end thereof containing the smallest mesh.

5. A rock and sand heater and grader comprising a heating chamber; a series of

inclined grading chutes mounted within the chamber and arranged to form tortuous heat passages through said chamber; a revolving screen mounted within said chamber and 5 above the chutes therein and arranged to grade and separate rock and sand delivered therein and to deliver separate grades to separate chutes; inclined baffle plates arranged below the screen and above the 10 chutes and arranged to receive the graded

material from said screen and to deliver the same to said chutes through the tortuous heat passages; means for delivering material to the screen at the end thereof containing the smallest mesh; and means for 15 heating the heating chamber.

In witness whereof I hereunto set my signature.

JESSE J. BROWN.
